UNITED STATES PATENT OFFICE.

CHARLES SPIRO, OF NEW YORK, N. Y.

TYPE-WRITING MACHINE.

SPECIFICATION forming part of Letters Patent No. 476,903, dated June 14, 1892.

Application filed February 10, 1891. Serial No. 380,929. (No model.)

To all whom it may concern:

Be it known that I, CHARLES SPIRO, a citizen of the United States, residing at New York, in the county of New York, State of New York, have invented certain new and useful Improvements in Type-Writing Machines, of which the following is a specification, reference being had therein to the accompanying drawings.

10. This invention has relation to certain new and useful improvements in type-writing machines, the operation, construction, objects, and advantages of which will be hereinafter described, and the novel features thereof will be particularly pointed out in the claims.

Referring to the drawings, Figure 1 is a side elevation of an improved type-bar and type-selecting adjuncts which constitute a part of this my invention. Fig. 2 is a perspective of 20 the principal adjuncts of the type-bar shown in Fig. 1. Fig. 3 is a modified construction of type-bar and type-selecting adjuncts, a portion of the bar being shown detached. Fig. 4 is a side elevation showing the devices for 25 operating the type-selecting means illustrated in Fig. 3. Fig. 5 is a side elevation of a key-lever and key, the latter being shown in section parallel with and at right angles to the key-lever. Figs. 6 and 7 are a plan and vertical section, respectively, of a portion of the platen shown in end elevation in Fig. 1 and means for removably connecting the platen with the carriage. Fig. 8 is a plan of an improved ink-pad adapted to the printing characters employed in this my present invention. Fig. 9 is a plan of the type-selecting device 35 illustrated in Fig. 3.

Like letters refer to like parts in all the figures.

40. Let A represent the platen of an ordinary type-writing machine, and A' the end casting or gudgeon-plate thereof.

B represents the riser or standard, usually formed on the ends of the carriage B'. The 45 end plate A' has a pin or stud A³ projecting therefrom, into which is seated a screw A³. Passing through the riser or standard B is a hollow journal B², adapted to fit the pin or stud A² and having at or near its end a slot 50 B³, communicating with a concave seat B⁴, adapted to fit the head of the screw A³. Each end of the platen is constructed as thus de-

scribed, so that when it is desired to exchange one platen for another—as, for example, a hard-rubber platen for manifolding or a softer-rubber platen for ordinary work—all that is necessary to do is to loosen the screw A³ and to draw the journal B² away from the pin or stud A², as clearly shown in Fig. 6, and until these parts are separated from each other, when the platen can be bodily removed from the carriage and another substituted therefor, when a reversal of the movement of the several parts securely binds the platen in position for operation and use.

C represents the key-lever of the machine, which may be either straight or curved, as shown by dotted lines, the latter form being employed to raise keys into the plane of the various banks of the board of keys. In 70 either case the key-lever is provided with a hole C' and at its edge immediately opposite the hole with insets or shoulders C², the hole and insets being for the reception and retention of a key, which is constructed in the following manner: A cup-shaped disk D, of zinc or other suitable metal, is perforated and riveted to a shouldered bifurcated spindle D', of brass or other suitable material, and within the disk are placed, first, a disk of card-board 80 or other suitable material, having imprinted thereon the letter or character which the key is to represent and above and protecting the same a disk of celluloid, glass, or other suitable material D³. After these disks are placed within the body of the key the upper edge thereof is spun inwardly and downwardly upon the outer disk, as shown at D⁴. The bifurcations of the spindle D' are a distance apart, adapted to receive between them the key-lever C, and 85 the ends of the bifurcations are forced laterally toward each other and into the holes C' in the key-lever. In this manner the key has a broad bearing upon the edge of the key-lever, which prevents oscillation in one direction of the key on the lever, while the bifurcations of the spindle have a long bearing against the opposite sides of the key-lever to 90 prevent oscillation in another direction, while the compression of the ends of the spindle 95 within the opening C locks the parts together with great firmness, and this without the use of solder.

In Fig. 3 I have shown one form of type-

bar and type-selecting devices to be employed in connection therewith. In this instance on the base, table, or plate E of a type-writing machine or on any other part of said machine which is adapted to receive and support the type-bars and their adjuncts I mount a bracket E', which may be secured to the plate E by a screw or screws E². In this bracket, and pivotally connected therewith by means of a screw E², is what I shall designate as a "type-bar carrier" F, which is constructed in such a manner that it can be oscillated on its pivot E³ and will carry and permit the rotation of a type-bar G therein or thereon. To adapt it for these purposes, various forms of construction may be adopted, and among the requirements are that it shall be provided with an eye F' or equivalent device for the connection of a draw-rod F², extending to the type-lever C, which lever is understood to be provided with the usual returning-spring or its equivalent, so that when it is once depressed it will be by said spring or equivalent device returned to its normal position. This construction is so common in the art that I have not deemed it necessary to illustrate the same.

Referring more particularly to Fig. 3, the type-bar G is grooved, as at G', for the reception of a pin or screw F³, seated in the carrier, and said groove is disposed along first one side of said type-bar, thence diagonally around, and thence along the opposite side of said type-bar, so that when said bar is reciprocated longitudinally through the carrier F by any means it is caused to rotate or semi-rotate thereby, as will hereinafter clearly be seen, bringing or causing the printing character (in moving from the printing-point on the platen to its normal position of rest) to move by the turning of the type-bar, so as to present said printing character or type squarely against an inking-pad H, (see Figs. 1 and 8,) whereby there is provided in a bar-machine a mechanism with which printing direct from the type and without the interposition of an inking-ribbon is accomplished. A spring G³ is coiled about the type-bar and connected at one end to the bar and at the other end to the carrier. When a type-bar is projected through the carrier, the spring is brought under tension, so that in the return movement of the type-bar—that is, in returning from the printing-point to an upright position—the bar is by said spring moved longitudinally, so that the pin F³, Fig. 3, engaging the slot in the bar, causes the same to rotate and to present the printing character against the inking-pad.

As thus far described it will be noted that but a single printing character has been mentioned as being provided on the type-bar and that with such single printing character printing direct from the type-bar by causing it to rotate on or with the type-bar is accomplishable, and I therefore do not restrict my invention to a use of more than one printing character on each type-bar; but in view of the fact

that the construction shown and described occupies more space at the pivot of the type-bar than in an ordinary bar-machine, and for the purpose of utilizing the old expedient of upper and lower case characters on each type-bar, I have shown and will now proceed to describe that construction and modification thereof whereby I may employ more than one printing character on each type-bar.

Referring again more particularly to Fig. 3, it will be seen that the printing character a is at the printing-point of the platen A (indicated by a curved line) and that the printing character a' is not in contact with the platen. It therefore remains to specify the means employed for selecting a desired character. It will be noted that the slot or groove G' in the type-bar G extends for such a distance that the pin or screw F³ remains therein not only while the printing character a is at the printing-point, but also when the type a' is at the same point, so that the rear end of the type-bar G (which may or may not be provided with a rounded hardened head G² and which is movable or fixed upon the rod, as desired, solely for the purpose of reducing the friction and lengthening the life of the type-bar at this point) can move longitudinally within the carrier without rotating, thus producing a limit or stop to the rotation of the type-bar, and for such a distance as to bring the type a to the printing-point. In such a movement of the type-bar the head G² would occupy the position indicated by dotted lines, Fig. 3. Now in order to determine in which of the two positions shown in said figure the type-bar shall be placed in the selection of a desired printing character I have provided a selecting-plate I, which has thereon a series of curved paths I' I², on which the head G² may move, which paths are in different planes, distanced from each other as are the type a a'. The screw or screws I³, by which the selecting-plate is connected with the table E, passes through slots I⁴ in the plate, whereby it is adapted to be moved to bring either of the curved paths thereof opposite the head G² of a type-bar. At the base of the plate I these paths are coincident, so that when the type-bar is upright the plate can be moved readily, so as to select either of the paths, and thus to determine the extent to which the type shall be projected through the carrier. The curvature of either of the paths I' I² is sufficient to cause such a reciprocation of the bar as will turn it to present the type thereon against the inking-pad and when brought to the printing-point against the paper.

I have illustrated in Fig. 4 one of the many ways of moving a selecting-plate I, which involves the use of a link I⁵, a bell-crank lever I⁶, and a ligament or draw-rod I⁷, extending to and connected with a type-bar C. These devices move the plate in one direction, while a spring I⁸, connected at one end with the selecting-plate and at the other end with the table E by a pin, screw, or staple I⁹, moves the

plate in the opposite direction. Any other selecting device may be employed.

In Figs. 1 and 2 I have illustrated a modified construction for the purpose of rotating the type-bar and for the purpose of selecting one of two or more characters mounted on said type-bar. In this instance the type a and a' are upon the periphery of a segmental block a^2 , Fig. 8, which is rigidly mounted on the end 10 of the type-bar G . Now it will be seen that by rotating to a greater or less extent the type-bar G in the carrier F either one of the printing characters on the block a^2 may be brought to the printing-point. In this instance I have illustrated a miter-pinion J , which is secured to the bar G , and a fixed sector K . The fixed sector is or may be an extension of an arm of the bracket E' , and it is provided with the teeth K' , of such form and 15 in such position as to mesh with the pins J' of the miter J . There are in this instance three of said pins and teeth. A stop J^2 occupies a position as one of the series of projecting members of the miter-gear and is adapted 20 to be brought into contact with the body of the holder F , as clearly shown in Figs. 1 and 2. In this construction there is also employed a lever L , mounted loosely on the pivot E^3 of the type-bar, which lever may be vibrated by 25 any suitable means, such as the friction of the type-bar upon the lever. One end of this lever is adapted to be interposed between the body of the holder F and the stop J^2 whenever the other end of said lever comes into 30 contact with a tooth I' of the plate I , as clearly 35 shown in Fig. 1, and so as not to become interposed between said stop and the body of the holder when said end of the lever comes at a point between two of the teeth I' of the 40 selecting-plate I . The object of this lever L is to limit the rotative movement of the type-bar G , so that a printing character or type a shall be brought to the printing-point instead of the printing character or type a' of the 45 block a^2 , mounted on the type-bar G . In this form of printing character I find that more uniform and satisfactory inking of the type is produced by corrugating the inking-pad H , (see Fig. 8,) so that each of the printing-type 50 a a' will have a substantially squared or flat contact with the inking-pad.

In the rapid operation of the type-bars hung as hereinbefore described there may be a tendency to overcome the tension of the 55 spring G^3 to such an extent that when the type are brought suddenly down upon the platen the tangential effect of the force applied to the bar-carrier would be to project the type beyond the printing-point transversely, so that I purpose to provide locking-pins M M , between which lateral projections M' on the type-bar shall enter as the bar approaches the printing-point, thus securing accurate alignment in the printing.

65 In Fig. 1 the spring G^3 exerts simply a torsional tension on the bar G , so as to keep the teeth or pins J in contact with the teeth of

the plate J' , while in the form illustrated in Fig. 3 the only necessary tension of the spring is longitudinal, so as to reciprocate the type-bar in one direction to keep its head in contact with one or the other on the paths I' I^2 of the selecting-plates. The torsional effect in this modification is extremely slight and non-essential, as the turning of the bars is positively accomplished by the pin and groove.

I have discovered by use that zinc keys are preferable to nickel-plated keys for the following reasons: This material while being 70 used takes on a moderate polish or gloss, and will retain the same by an ordinary use of the keyboard. This moderate gloss is much preferable to the glaring brightness of nickel-plated keys as usually constructed and is less 75 trying to the eyes of the operator, while the celluloid disks give a touch and feeling to a key which are not present where glass is used to cover the letter-disk of the key, nor is it so liable to be broken by use or jarring or when 80 spinning the edge D^4 down upon it when making 85 the key.

It is apparent that the type-block a^2 may be rotatably mounted on the type-bar G , and that the rotating device, whether a gear or slot-and-pin construction or any other well-known mechanical elements, would in that case be operatively connected with said block 95 for turning the same to bring the type thereon against an ink-pad after each impression instead of with the type-bar when said block is 100 rigidly connected therewith.

What I claim is—

1. An oscillatory type-bar, in combination with a bar-carrier and with means for rotating the bar and for reciprocating the bar within the carrier by the oscillation of the bar, substantially as specified.

2. A pivoted type-bar, a type-bar carrier pivotally connected with the bracket, and means for reciprocating the type-bar for varied distances within the carrier, substantially as specified.

3. A pivoted type-bar carrier, a reciprocating type-bar provided with multiple printing characters, and means for selecting the character of the type-bar which is to be brought to the printing-point, substantially as specified.

4. The combination, with a bracket, of a type-bar carrier, a rotative and reciprocating type-bar, and means for reciprocating and for rotating the type-bar to bring the printing character into contact with an inking-pad and with the platen of a type-writing machine, the rotating and reciprocating devices being arranged in the path of the type-bar, substantially as specified.

5. A type-bar and means for its oscillation and reciprocation to and from the platen to present a type to the platen and to turn the bar and present said type to an inking-pad, substantially as specified.

6. An oscillatory reciprocative rotatable type-bar, in combination with means for re-

reciprocating the same and with means arranged in the path of the bar as it oscillates for the purpose of rotating said bar, substantially as specified.

5 7. A rotatable reciprocative type-bar pivotally mounted for oscillation, and means arranged in the path of its oscillatory movement to rotate and means for reciprocating said bar, and means for determining the extent of said rotation and reciprocation, substantially as specified.

8. A type-bar having a multiplicity of printing characters thereon and mounted for oscillation and reciprocation, in combination with 15 means for selecting one of the characters thereon to be brought to the printing-point, substantially as specified.

9. A reciprocative type-bar having a plurality of printing characters and mounted for 20 oscillation, in combination with means for selecting a character on the bar to be brought to the printing-point and means for rotating said bar so as to bring the printing character into direct contact with an inking-pad after 25 each impression, substantially as specified.

10. The combination, with a pivoted type-bar carrier, of a type-bar and means for its rotation and reciprocation and a stop to determine the limit of its rotation, substantially as specified.

11. The combination of a type-bar carrier pivoted for oscillation, a type-bar movably mounted in the carrier for reciprocation, and a spring connecting the bar and carrier, substantially as specified.

12. The combination of a type-bar carrier pivotally mounted for oscillation, a type-bar mounted for reciprocation and rotation in the carrier, and a character-selecting device provided with paths for the type-bar, substantially as specified.

13. The combination, with a platen, of a journal movably fitted to the pin of the platen

and means for non-rotatably securing the two together, substantially as specified.

14. The combination, with a platen and with the standard or bracket of a carriage, of a longitudinally-movable journal slotted for the reception of a screw mounted in the gudgeon or pin of the platen proper, substantially as specified.

15. The combination, with the platen and casting and pin or gudgeon, of a screw mounted in said pin or gudgeon and a journal adapted to receive said pin or gudgeon and the screw thereof and having a seat for the head of said screw, substantially as specified.

16. In combination with a key-lever having a hole therethrough, a key provided with a bifurcated stem and adapted to rest bodily upon the edge of the lever to prevent oscillation and having its stem forced rigidly into the hole thereof, substantially as specified.

17. The combination, with a key-lever having an inset at one edge and a hole in line with the inset, of a key having a bifurcated stem adapted to be forced rigidly into the hole of the key-lever, substantially as specified.

18. An oscillatory, reciprocative, and rotatable type-bar, in combination with means arranged in the path of the bar as it oscillates for the purpose of rotating said bar and with means for giving and determining the extent of its reciprocation, substantially as specified.

19. The combination of a type-bar, means for rotating said bar, means for determining the extent of its rotation, and a spring encircling said bar and connected thereto at one end and at the other to a non-rotatable part, substantially as specified.

In testimony whereof I affix my signature in presence of two witnesses.

CHARLES SPIRO.
